UNITED STATES PATENT OFFICE.

NATHALIA C. ANDERSON, OF FRANKLIN, MINNESOTA.

COLLAPSIBLE NEST.

Application filed May 7, 1921. Serial No. 467,707.

To all whom it may concern:

Be it known that I, NATHALIA C. ANDERSON, a citizen of the United States, residing at Franklin, in the county of Renville and 5 State of Minnesota, have invented certain new and useful Improvements in Collapsible Nests; and I do hereby declare the following to be a full, clear, and exact description of the invention, such as will enable others 10 skilled in the art to which it appertains to make and use the same.

This invention relates to a hen nest and particularly to a portable nest capable of being readily transported to the desired location where it will be disposed upon a suitable support.

It is an object of this invention to provide a nest made of sheet material, preferably metal, and so arranged that the same can be 20 very readily cleaned or fumigated and thus kept in very sanitary condition.

It is a further object of the invention to construct the nest of plate members which are pivoted together partly by detachable 25 pivots, the nest thus being capable of being collapsed into a small space for shipment or storage, the same, however, being arranged to be quickly and easily assembled.

These and other objects and advantages 30 of the invention will be apparent from the following description made in connection with the accompanying drawings, in which like reference characters refer to the same parts throughout the different views, and in 35 which—

Fig. 1 is a perspective view of the nest in supported position;

Fig. 2 is a transverse section of the same taken on line 2—2 of Fig. 1, looking in the 40 direction of the arrows;

Fig. 3 is a partial section taken on line 3—3 of Fig. 1 looking in the direction of the arrows; and

Fig. 4 is a plan view of the nest in partially collapsed position with the bottom, top and rear members removed.

Referring to the drawings:

The nest comprises a front plate or member 1. The ends of this plate are notched 50 or cut out to form tongues which are bent inwardly on the inside of the plate to form hinge lugs 1^a. End plates 2 are provided, one edge of which is also notched to form tongues, which are also bent in to form 55 hinge lugs 2^a. These lugs are arranged to

fit between the lugs 1^a of the front plate in alignment therewith and the front plate 1 and side plates 2 are thus pivotally connected by pivot pins 3 passing through the lugs 1^a and 2^a. A partition member 4, similar to the 60 end members 2, is also pivotally secured to the inside of the front plate by hinges adjacent the top and bottom edges of said plate 1, which hinges are riveted or otherwise secured to the two plates. The plates 2 and 4 65 have laterally bent lugs 4^a projecting at right angles therefrom at the top of their rear edges and a top plate 5 is pivotally secured to these lugs by small headed and nutted bolts 6 passing downwardly through 70 said plate and the lugs. The plate 5 is also notched along its longitudinal edges to form 75 tongues which are bent downwardly and inwardly to form pivot or hinge lugs 5^a. A top plate or cover 7 has one longitudinal edge notched and bent to form hinge lugs arranged to fit between the hinge lugs 5^a and is connected thereby to the plate 5 by a removable pivot pin 8, one end of which is bent at right angles to form a handle. A rear 80 closing plate 9 also has one longitudinal edge formed with hinge lugs co-operating with the lugs 5^a and this plate is pivoted and connected to the plate 5 by a removable pivot pin 10, one end of which is also bent laterally to form a handle.

The side members 2 are formed adjacent the lower rear edges with spaced hinge lugs 2^b and a rear plate 11 is provided with a hinged lug at each end fitted between the 90 two lugs 2^b, by means of which it is pivotally connected to the end plates 2 by suitable pivots 11^a. The plate 11 is also pivotally secured to the partition plate 4 by the hinge 4^b, the sections of which are riveted or otherwise suitably secured to the plates 4 and 11. The plate 11 is formed along its bottom edge with spaced hinge lugs and a bottom plate 12 has one edge formed with hinge lugs arranged to align with and alternate with the 95 lugs of plate 11, so as to be pivotally connected to said plate by a removable pivot pin 13, one end of which is bent laterally to form a handle portion. The other longitudinal edge of the member 12 has secured thereto some suitable fastening member, such as a hook 12^a adapted to co-operate with a fastening member on the front plate 1, such as the staples 1^b shown as secured to the plate and projecting therefrom at its front por- 100

tion to receive the hooks 12^a. The plate 12 is thus held in substantially horizontal position in contact with the plate 1 to form the bottom of the nest.

5 The nest is adapted to be disposed on a suitable support and to this end, the front plate 1 and end plates 2 have secured thereto the angle members 14, one side of which projects from said plates and are adapted to 10 rest upon supporting members *a* carried on suitable legs *b*. Preferably, the nest is disposed in close proximity to a wall of the hen house or other structure and a support *a* is shown as extending into contact with such 15 a wall *c*. With the nest in position, the rear plate 9 is preferably placed with its rear edge in contact with the wall, said plate extending in substantially horizontal position. If desired, the edge of said plate may 20 be provided with fastening means 9^a and co-acting fastening means 9^b, such as the hooks shown, may be attached to the walls *c* to insure that the plate 9 will be held in the 25 desired position.

25 It is well known that hens in seeking a nest prefer a somewhat darkened place and for this reason the nest is preferably arranged as shown and described. The hens are supposed to enter the nest from the rear through 30 the space and between the plate 11 and the top plate 5. A perch *a*¹ is shown as extending between the supporting members *a* and the rear of the nest upon which the hens will first jump and will then jump from 35 this perch into the nest or onto the edge of plate 11.

With the structure described, it will be seen that the nest is capable of being collapsed into a small space. This is an important feature when it is desired to ship the 40 nest or to store the same when not in use. When the nest is to be collapsed, the removable pivots 8, 10 and 13 are preferably withdrawn and the detached plates 7, 9 and 45 12 can thus be laid one on top of the other in compact arrangement. The pivot pins will preferably be replaced in the edges of these plates through the pivot lugs thereon. With the said plates removed, the nest can then be 50 swung into collapsed position as indicated in Fig. 4 and can thus be laid practically flat, the width of the plate 5 and the width of the channel members 14 limiting the transverse dimension of the collapsed article. As 55 the plate 5 is attached by the nutted screws or bolt 6, this plate can also be quickly removed as desired and placed lengthwise in flat position with the other plates. The nest is thus capable of being shipped or stored in 60 a flat compact package in which there is practically no chance of the plates being damaged or distorted. The nest, it can also be readily seen can be quickly and easily assembled. While the device is preferably 65 made from sheet metal, it will also be un-

derstood that wood or other material may be used as desired. It will also be observed that by the hinge bottom plate 12, the nest can be quickly and easily cleaned. If it be desired to prevent the entry of hens into the nest, such as when the same is being used for setting hens, the plate 9 can be allowed to swing down to close the space between plate 11 and the top of the nest.

70 While the invention is not limited to any particular size and can be made of any desired dimensions, in practice it has been found that a nest having the end plates substantially fourteen inches square with the ledges 14, substantially six inches from the bottom thereof constitutes a very satisfactory and practical nest.

75 It will, of course, be understood that various changes may be made in the form, details and arrangement of the device without departing from the scope of applicant's invention, which generally stated consists in the matter shown and described and set forth in the appended claims.

80 85 What is claimed is:—

90 95 1. A collapsible nest comprising a front plate, end plates pivoted thereto and extending at right angles therefrom, a rear plate pivoted to the edges of the end plates remote from the front plate, the upper edge of said plate being spaced from the upper edge of said end plates, and a top plate overlying the end plates in the rear thereof, and being pivoted thereto whereby all of said plates may be swung on the pivots to bring the same into 100 a small space in collapsed position.

105 2. The structure set forth in claim 1, said top plate having a front cover plate pivotally and detachably secured thereto and arranged to overlie the end and front plates.

3. The structure set forth in claim 1, said top plate having pivotally and detachably connected to its front side a cover plate adapted to overlie the front and end plates and having pivotally and detachably secured 110 to its rear side a rear plate adapted to hang from its pivot to close the rear of the nest.

4. A collapsible nest having in combination, a front plate, end plates and a partition plate pivotally secured thereto and projecting at right angles therefrom, a rear plate pivotally secured to said end plates and partition at the side remote from the front plate, and a top plate pivotally secured to the end plates and partition whereby all of said plates may be swung on their pivots into collapsed position.

115 5. A collapsible nest comprising pivoted front and end plates, and supporting means secured to said plates comprising angle bars having a horizontal portion projecting outwardly therefrom and extending throughout the length of said bars.

120 6. A demountable and collapsible hen nest having in combination front and rear 125 130

sides and ends pivoted along their vertical edges, a plate extending along the top of the rear side and pivoted thereto by vertical pivots, said plate having hinge means at its 5 front and rear edges and a top plate and rear plate, respectively hingedly connected to said means.

7. A demountable and collapsible hen nest having in combination, front and rear 10 sides and ends pivoted along their vertical edges, a plate extending along the top of the rear side and pivoted thereto by vertical pivots, said plate projecting at each side of said rear plate and having spaced pintle receiving lugs at its front and rear longitudinal edges, a top plate having lugs co-operating with the lugs on the front edge of said plate, a rear plate having lugs co-operating with 15 the lugs on the rear side of said plate, and

removable pintles connecting said top and 20 rear plates to said plate.

8. A collapsible poultry nest structure having in combination, front and rear side and end members pivoted along their vertical edges, and a narrow horizontal member 25 extending along the top edge of said rear plate and pivoted thereto by vertical pivots, said narrow member adapted to have top and rear plates hingedly connected thereto whereby said front and rear side and end 30 members may be collapsed substantially in one plane with said narrow member thereon.

In testimony whereof I affix my signature in presence of two witnesses.

NATHALIA C. ANDERSON.
